UNITED STATES PATENT OFFICE.

JOHN M. ALEXANDER, OF CEDAR RAPIDS, IOWA, ASSIGNOR OF ONE-THIRD
TO HARRY D. CONE, OF SAME PLACE.

HAT AND UMBRELLA RACK.

SPECIFICATION forming part of Letters Patent No. 665,846, dated January 8, 1901.

Application filed March 27, 1900. Serial No. 10,364. (No model.)

To all whom it may concern:

Be it known that I, JOHN M. ALEXANDER, a citizen of the United States, residing at Cedar Rapids, in the county of Linn and State 5 of Iowa, have invented certain new and useful Improvements in Hat and Umbrella Racks; and I do hereby declare the following to be a full, clear, and exact description of the invention, such as will enable others skilled in 10 the art to which it appertains to make and use the same.

The object of this invention is to provide a convenient support for a hat and an umbrella or cane attachable to church-pews or 15 other places where required.

The nature of the invention will be fully disclosed in the description and claims following, reference being had to the accompanying drawings, in which—

20 Figure 1 is a view in perspective, illustrating a device embodying my invention as applied to a church-pew. Fig. 2 is an enlarged view of the same detached.

Similar letters of reference indicate corresponding parts.

In the drawings, A designates a church-pew back to which are attached suitable supports B for hooked brackets C. These brackets are connected at C' by a bail D, having a 30 middle curve at D' to take the crown of a hat E. The brackets are provided with hooks C², which serve as a support for an umbrella or cane, as illustrated in Fig. 1. In practice the brackets and bail are formed of wire 35 bent in substantially the form shown. At C² and C¹ the ends of the wire forming each bracket are bent down to form a pivot engaging the support B, which may be a simple screw-eye, as shown. At C' an eye is formed 40 to connect with a terminal eye D² at each end of the bail. A portion of the body of each bracket is looped back upon itself to form the hook. So constructed the device may be

folded back against the back of the pew or whatever it may be attached to when not in 45 use. Its construction is such as to render it very convenient in connection with church-pews, as no provision is usually made for holding hats, and they are accordingly laid on the floor or in the seat and likely to be kicked 50 or crushed.

It is not absolutely necessary that the brackets should fold back; but this feature is desirable, particularly in connection with church-pews, as it leaves an unobstructed 55 passage for the occupants in entering or leaving the pew.

Having thus described my invention, what I claim as new, and desire to secure by Letters Patent, is—

1. A hat and cane or umbrella support, comprising a pair of brackets provided with cane-supporting hooks, a bail having a downward, middle curvature adapted to take a hat-crown, pivotally connecting said brackets a short distance from the wall or other support, and means substantially as described for mounting said brackets pivotally on a wall, so as to swing sidewise when not in use.

2. A hat and cane or umbrella support, comprising a pair of wire brackets provided with terminal pivots to engage screw-eyes in the wall or other support, eyes to connect with a hat-supporting bail, and bent to form cane-supporting hooks, a hat-supporting bail having terminal eyes to connect with the eyes in the brackets and a middle curved portion to take the hat-crown, and screw-eyes to support the bracket-pivots, substantially as described.

In testimony whereof I affix my signature in presence of two witnesses.

JOHN M. ALEXANDER.

Witnesses:

GEO. H. SMITH,
J. M. ST. JOHN.
